UNITED STATES PATENT OFFICE.

FRANK COLONNESE, OF NEW YORK, N. Y., ASSIGNOR OF ONE-THIRD TO CHARLES BOCCIA, OF NEW YORK, N. Y.

FOLDING CAMERA.

1,160,045.

Specification of Letters Patent.

Patented Nov. 9, 1915.

Application filed February 12, 1915. Serial No. 7,794.

To all whom it may concern:

Be it known that I, FRANK COLONNESE, a subject of the King of Italy, residing at New York, in the county of New York and State of New York, have invented new and useful Improvements in Folding Cameras, of which the following is a specification.

This invention relates to collapsible cameras of the reflex type and it consists in the novel features hereinafter described and claimed.

In this form of camera a ground glass screen is usually mounted in the case approximately at a right angle to the focal plane and inasmuch as these parts have fixed relation it has heretofore been impossible to collapse the case in order that the outfit may occupy small space when in transit.

It is the object of the present invention to provide means for swinging or folding the ground glass screen and the mirror with relation to the focal plane in order that the said parts may be compactly assembled when the case is collapsed or folded.

In the accompanying drawings:—Figure 1 is a side elevation of the camera showing the parts extended. Fig. 2 is a similar view showing the parts collapsed. Fig. 3 is a similar view showing the parts collapsed and having parts broken away. Fig. 4 is an edge elevation of the screen and mirror and connecting parts. Fig. 5 is a perspective view of the screen and mirror showing the said parts disconnected and separated. Fig. 6 is a side elevation of the shutter releasing means. Fig. 7 is a detailed perspective view of a lever adapted to be used for swinging the mirror out of the cone of light.

As illustrated in the accompanying drawing the camera includes a foldable case 1 having mounted upon the top thereof a foldable hood 2. A bellows 3 is connected with the forward side of the case 1 in the usual manner and carries a lens holder 4 which in turn is adjustably supported in a frame 5. The frame 5 is adjustably mounted upon a bed 6 in the usual manner and the said bed is hingedly connected with an outer case 7 which is somewhat smaller in end elevation than the inner case 1 hereinbefore referred to. The inner case 1 is connected at its rear edge with the outer case 7 and the outer case 7 is provided at its rear side with a plate holder 8 and when the plate is in position in

the holder it constitutes what will be herein-after referred to as the focal plane. Links 9 are pivotally connected with the bed 6 and slidably engage the sides of the outer casing 7 and serve as means for holding the bed 6 in proper position with relation to the case 60 7 when the parts are in extended positions as shown in Fig. 1 of the drawings. When the parts are in the position as shown in Fig. 1 the lens which is carried by the lens holder 4 is adapted to cast or direct a pencil 65 of light upon the focal plane hereinbefore referred to. The hood 2 is provided with an inflexible side 10 which is hingedly connected with the end walls of the case 7 and links 11 are pivotally connected with said 70 inflexible side 10 and also slidably engage the end walls of the case 7 and are adapted when the parts are in extended position to hold the side 10 and the hood 2 extended as shown in Fig. 1 of the drawing. 75

A roller 12 is journaled for rotation in the lower portion of the case 7 and this roller is of the usual spring actuated type employed in cameras of this kind. A roller 13 is journaled for rotation at the upper portion of 80 the case 7. A shutter curtain 14 of the usual pattern is arranged to wind upon the rollers 12 and 13, the said curtain as it unwinds from one roller winds upon the other, the curtain during operation unwinding from 85 the roller 13 and winding upon the roller 12. A handle 15 is pivotally mounted upon the shaft of the roller 13 and may be used for the purpose of rewinding the curtain upon the said roller 13. A gear wheel 16 90 (best shown in Fig. 6 of the drawing) is mounted upon the shaft of the roller 13 and meshes with a gear wheel 17 which is journaled at the side of the case 7. A ratchet 18 is fixed with relation to the gear wheel 17 95 and is provided with a single tooth 19. A bell crank detent 20 is fulcrumed at the side of the case 7 and is provided at one end with a pawl 21 adapted to engage the tooth 19 of the ratchet and normally hold the 100 same against rotation. A spring 22 is fixed to the side of the case 7 and bears against the end portion of the bell crank detent 20 and serves to normally hold the pawl 21 in the path of movement of the tooth 19 of the 105 ratchet 18. The detent 20 is provided at that end other than the end which carries the pawl 21 with an outstanding lug 23 the

object of which will be hereinafter explained.

A shaft 24 is journaled at its end portions in the opposite sides of the case 7 and carries a ground glass screen 25 of the usual pattern. An angular block 26 is fixed to the shaft 24 and bears against the free end portion of a spring 27 which is attached to the side of the case 7. A handle 28 is attached 10 to one end of the shaft 24 and may be used as means for turning the said shaft. The faces of the edge of the block 26 are so disposed with relation to each other that when one face of the said block is moved in contact 15 with the free end portion of the spring 27 the screen 25 is held in a horizontal position as shown in heavy lines in Fig. 4. When the said screen is in this position it is in a plane approximately at a right angle to the 20 focal plane of the camera. When the shaft 24 is turned so that the next adjacent face of the edge portion of the block 26 is brought in contact with the spring 27 the screen 25 is held in a position approximately parallel 25 with the focal plane of the camera as indicated in dotted lines in Fig. 4 of the drawing.

A shaft 29 is supported at its end portions at the opposite sides of the case 7 and a mirror 30 is mounted for pivotal movement upon the said shaft. The lug 23 which is carried by the detent 20 projects into the path of movement of the edge portion of the mirror 30. Arms 31 are fixed to the shaft 35 29 and swing about the axis of the shaft as the said shaft is turned. The said arms 31 are provided with inwardly disposed ledges 32 upon which the mirror 30 may rest at times. One of the arms 31 is provided with 40 a longitudinally disposed slot 33. A link 34 is pivotally connected at one end with one edge of the screen 25 and the said link is provided at its other end with an inwardly disposed pin 35 which lies in the slot 33 of 45 that arm 31 provided with the said slot. A rod 36 is pivotally connected at one end with one edge of the mirror 30 and at its other end is pivotally connected with the inner arm of a lever 37. The said lever 37 is ful- 50 crumed in one side of the case 7 and its outer arm may be used as means for swinging the lever.

When the parts of the camera are folded they are in the position as shown in Fig. 3 of 55 the drawing. When it is desired to extend the parts of the camera the bed 6 is swung down into alignment with the lower side of the case 7 and the frame 5 is passed out along the said bed to a position approxi- 60 mately the same as that shown in Fig. 1 of the drawing. Inasmuch as the inner case 1 is connected with the frame 5 through the bellows 3 the outward movement on the part of the said frame 5 extends the case 1 and 65 the inflexible side 10 of the hood 2 is then

swung up into the position shown in Fig. 1. Thus the hood 2 is extended over the case 1. By using the handle 28 the shaft 24 is then turned so that the screen 25 is swung from a position approximately parallel with the 70 focal plane of the camera to a position at right angles thereto as indicated in dotted lines in Fig. 1 and as shown in heavy lines in Fig. 4. As the said screen 25 is thus moved the pin 35 carried by the link 34 75 moves along the slot 33 until it encounters the upper end thereof and then the said link swings that arm 31 to which it is attached which in turn partially rotates the shaft 29 and thus both of the arms 31 move together. 80 Inasmuch as the mirror 30 is pivotally mounted upon the shaft 29 and rests upon the ledges 32 of the arms 31 the said mirror is swung from a position approximately parallel with the focal plane of the camera to a 85 position at an angle with relation to the same as shown in dotted lines in Fig. 1 and in heavy lines in Fig. 4. When the parts are in these positions the camera is ready for use. In the operation of taking a picture 90 the camera is positioned and the lens thereof focused in the usual manner and at the desired instant the operator depresses the outer end of the lever 37 whereby the inner end thereof is swung in an upward direction. 95 This moves the rod 36 longitudinally which in turn swings the mirror 30 up toward the screen 35 and beyond the cone of light which is directed into the body of the camera through the lens.

As the lever 30 moves in an upward direction its edge portion strikes the lug 23 upon the detent 20 and the said detent is swung upon its pivot against the action of the spring 22 and the pawl 21 is carried from 10 under the tooth 19 of the ratchet 18. When the said ratchet is thus released the tension of the spring which actuates the roller 12 comes into play and the shutter curtain 14 is unwound from the roller 13 and is wound 1 upon the roller 12. The said shutter curtain moves across the focal plane in close proximity to the same and as the opening in the curtain moves across the cone of light the sensitized surface of the plate which is 1 carried in the plate holder 8 is acted upon and the picture is taken.

It is to be understood that during the upward movement of the mirror 30 from the position shown in heavy lines in Fig. 4 the 1 said mirror does not engage the lug 23 until the said mirror arrives in the vicinity of the extremity of the upper end of its movement and when the said mirror is moved in an upward direction it is permitted to fall back 1 to the position shown in heavy lines in Fig. 4 almost immediately consequently as soon as the mirror 30 leaves the lug 23 the spring 22 comes into play and moves the detent 20 whereby the pawl 21 is carried back into

the path of movement of the tooth 19 of the ratchet 18. Therefore when the said ratchet describes one complete revolution the tooth 19 thereof encounters the pawl 21 and the 5 said ratchet 18 comes to a state of rest.

When it is desired to collapse or fold the parts of the camera the frame 5 is moved back along the bed 6 to position within the case 7 as shown in Fig. 3 of the drawing. 10 Prior to this the shaft 24 is turned whereby the screen 25 is swung from a position approximately at a right angle to the focal plane of the camera to a position approximately parallel with the said plane. 15 Through the connecting link 34 and that arm 31 with which it is attached the shaft 29 is turned whereby the said arms 31 are swung to approximately vertical positions. Inasmuch as the mirror 30 rests upon the inwardly disposed ledges 32 of the said arms the said mirror swings to a plane approximately parallel with the focal plane and assumes a position as shown in Fig. 3 of the drawing. 20 Therefore when the frame 5 has been moved in the case 7 the case 1 is collapsed and the inflexible side 10 of the hood 2 is swung down over the lens holder 4 and thus the said hood 2 is folded within the 25 case 7. The bed 6 is then swung up against the outer surface of the side 10 and is secured by means of a clip 38 which is attached to the edge portion of the inflexible side 10. The said inflexible side 10 is provided at a point adjacent that part thereof 30 which is pivotally connected with the case 7 with a handle 39 by which the camera may be carried when the parts are folded

and collapsed as shown in Fig. 3 of the drawing. Therefore it will be seen that a camera structure is provided in conjunction with a camera of the reflex type whereby the parts of the camera may be folded into small space or compass when it is desired to carry the apparatus. Also the parts are so arranged that the camera may 40 be easily and quickly set up or extended into operative position and when in such position the mirror may be easily and promptly moved beyond the cone of light and the movement of the said mirror effects the 45 release of the shutter curtain whereby the said curtain is moved across the cone of light and over the focal plane of the instrument. 50

Having described the invention what is 55 claimed is:—

A camera having a focal plane and means for directing a cone of light upon the same, an outer case of relatively small dimensions, an inner flexible case connected with the outer case, a shutter located between the 60 focal plane and the light directing means, a screen mounted for swinging movement in the inner case, a shaft turnably mounted in the outer case and having laterally disposed arms, a mirror normally resting upon the 65 arms, and a link operatively connecting the screen with one of the arms.

In testimony whereof I affix my signature in presence of two witnesses.

FRANK COLONNESE.
